CLAIM

The ornamental design for a telephone set, substantially as shown and described.

DESCRIPTION

FIG. 1 is a front isometric view from above of the top and left side of a telephone set showing my new design with the handset cradled in the stand;

FIG. 2 is a top plan view of the telephone set thereof; FIG. 3 is a front elevation of the telephone set thereof; FIG. 4 is a left side elevation of the telephone set thereof;

FIG. 5 is a right side elevation of the telephone set thereof;

FIG. 6 is a back elevation of the telephone set thereof; and

FIG. 7 is a bottom plan view of the telephone set thereof.

The partial showing of the cord in FIG. 1 by way of broken lines, and the fragmentary showing of cord in FIGS. 2, 3, 4, 6 and 7 is for illustrative expediency.
